UNITED STATES PATENT OFFICE.

GEORGE DALE, OF ROSELLE PARK, NEW JERSEY.

HYDRAULIC PRESS.

Application filed December 14, 1927. Serial No. 239,991.

- An important object of the present invention is to provide improved means for controlling the movements and the pressure of a hydraulic press ram.
- 5 Another important object of the invention is to simplify the operation of a hydraulic press by providing a valve device which is operated by fluid pressure to control the ram movements and pressure, the fluid pressure 10 for operating said device being under the control of a single manually operated valve. One operation of this latter valve actuates the fluid pressure device to first admit low pressure fluid to the ram cylinder for the first 15 portion of the working stroke of the ram and to later automatically admit high pressure fluid for the final portion of the stroke. Another operation of the valve causes the actuation of the fluid pressure device to release the 20 fluid in the ram cylinder and also admits fluid to the ram drawback means for retracting the ram. Thus the ram is entirely controlled through simple mechanism by only two manual operations.
- 25 Other objects will appear hereinafter.
- In the drawings:
- Fig. 1 is a longitudinal sectional view of my fluid pressure operated valve device;
- Fig. 2 a fragmentary longitudinal section 30 of said device with the valve in a different position;
- Fig. 3 a central sectional view of the control or pilot valve which cooperates with the fluid pressure operated device;
- 35 Fig. 4 a section taken on the line 4—4 of Fig. 3;
- Fig. 5 a section taken on the line 5—5 of Fig. 4;
- Fig. 6 a diagrammatic view of an entire 40 hydraulic press apparatus including my fluid pressure valve device and the control valve; and
- Fig. 7 a detail sectional view showing another adjustment of the control valve.
- 45 The fluid pressure operated valve device comprises a valve casing 1 which defines two cylinders 2 and 3 disposed in axial alignment and in endwise communication. The cylinder 2 is of greater diameter than the cylinder 3 and its outer end is closed by a cylinder head 4. The cylinder 3 is longer than the cylinder 2 and has its outer end closed by a cylinder head 5. These cylinder heads are bolted to the casing 1. Cylindrical linings or bushings
- 6 and 7 are fitted in the cylinders 2 and 3 respectively.
- 60 A piston valve 8 is mounted in the two connected cylinders 2 and 3 and formed with a head 9 and a reduced stem 10. The head is slidably fitted in the lining 6 of the large cylinder and the stem is slidably fitted in the lining 7 of the small cylinder. The piston head 9 is threaded at its outer end as at 11 and formed with a flange 12 at its inner end. An annular gasket 13 of channel form bottoms against the flange 12. A nut 14 is threaded upon the outer end of the piston head and a similar channel gasket 15 bottoms against said nut and is opposed to the gasket 13. Encircling the piston head is a cylindrical spacer sleeve 16 whose ends are received in the channels of the gaskets. The gaskets form a packing for the piston head and a tightening of the nut holds the gaskets and the sleeve assembled. The piston stem 75 is provided with similar packing means. The outer portions of the stem are reduced to accommodate the packing and to form a shoulder 17. There are two packing assemblies, similar to that upon the piston head, 80 mounted upon the piston stem and separated by a washer 18. The opposed gaskets 19 of the inner packing assembly bottom against the shoulder 17 and the washer 18 respectively and engage the spacer sleeve 20. The gaskets 85 21 of the outer packing assembly bottom against the washer 18 and a washer 22 and engage the spacer sleeve 23. A similar gasket 24 bottoms against the outer washer 22, and a nut 25 is threaded upon the outer end of the 90 piston stem and is formed to fit into the channel of the gasket 24. The packing assemblies and the washers are assembled endwise upon the stem and when the nut is tightened the various parts are held assembled. 95 The spacing sleeves 16, 20 and 23 of the piston packings are formed with apertures 16^a, 20^a and 23^a respectively to permit a free flow of fluid through the sleeves and around the gaskets. The gaskets, due to their form, are 100 expanded by the fluid to closely fit the cylinder linings.
- The valve casing 1 is formed with a flanged base 26 which is adapted to be secured to the upper end of the ram cylinder of a press. 105 The base is formed with a fluid passage 27 which leads to the ram cylinder and is bifurcated to provide two branches 28 and 29. The

branch 28 leads from an annular channel 30 extending around the inner face of the large cylinder 2 and the branch 29 leads from a similar channel 31 formed in the small cylinder 3. Circular rows of apertures 32 are formed in the lining 6 of the large cylinder to communicate with the channel 30, and the lining 7 of the small cylinder is similarly formed with apertures 33 which communicate with the channel 31. Formed in the large cylinder head 4 is a port 34 to admit fluid from the supply tank of the press to the cylinder 2 for causing one operation of the piston valve. The small cylinder head 5 is formed with a port 35 to admit fluid from the press pump to the cylinder 3 for another operation of the valve. Formed in the upper side of the casing 1 is a port 36 which extends downward through the cylinder lining 6 to the large cylinder 2 at the inner end of the latter. This port admits fluid from the supply tank. Similarly another port 37 is formed in the upper side of the casing, extends downward through the cylinder lining 7 and opens into the small cylinder 3 at a point intermediate the ends thereof. This port 37 admits fluid from the pump.

In Fig. 6 I have shown the valve device mounted upon the ram cylinder C of the press and operatively connected to the other parts of the press apparatus. The tank T of the apparatus has a fluid connection 38 leading to the port 34 of the valve device, a connection 39 leading to the port 36 of said device, a connection 40 leading to the pump P and a connection 41 leading to a pilot valve device 42. The device 42 comprises a valve seat 43, a valve chest 44 and a pilot slide valve 45 within the chest and slidably upon the seat. The valve has an operating stem 46 which is slidably mounted in stuffing boxes at the ends of the chest. Pivotaly mounted at one end of the chest is an operating lever 47 whose lower end is operatively connected to the valve stem 46. A fluid supply connection 48 leads from the pump P to the valve chest 44 and the valve seat 43 is formed with a port 49 which has a fluid supply connection 50 with the port 37 of the valve casing 1 for delivering fluid at pump pressure to the latter. The valve seat 43 is also formed with a pair of ports 51 and 51^a and with a pair of ports 52 and 52^a. The valve 45 is formed with two cavities 53 and 54 for connecting the ports of the two pairs respectively. A fluid connection 55 leads from the port 51 to the ram draw-back cylinders D of the press. The companion port 51^a leads to the supply tank connection 41. From the port 52 a fluid connection 56 leads to the port 35 of the fluid pressure operated valve device to provide fluid for operating the piston valve 8. The port 52^a leads to an exhaust connection 57 and has a restriction plug 58 threaded into it.

65 The pump P receives water from the sup-

ply tank T, and the connection 48 leading from the pump to the valve chest 44 is constantly open so that the chest is kept constantly supplied with high pressure pump fluid. The connection 38 leading from the tank T to the port 34 is also constantly open so that there is a constant and relatively low tank fluid pressure in the large cylinder of the casing 1 tending to force the piston valve 8 to the right, as viewed in the drawings. Assuming that the press ram R is elevated and it is desired to start it upon a working stroke to apply pressure, the control or pilot valve lever 47 is manually operated to move the valve 45 to application position as shown in Figs. 3, 4, 5, and 6. Fluid then exhausts from the draw-back cylinders D through the connection 55, the port 51 of the valve seat 43, the valve cavity 53, (see Fig. 3) the port 51^a in the seat and the connection 41 which leads to the supply tank T, the fluid being forced along this course by the gravitation of the ram and its connected parts. Simultaneously the valve cavity 54 (see Fig. 5) connects the ports 52 and 52^a so that fluid is free to exhaust from the small cylinder 3 of the casing 1 and relieve the pressure which tends to hold the piston valve 8 to the left. This exhaust is however, restricted by the plug 58. The purpose of this restriction is to delay or retard the movement of the piston valve to the right and permit fluid to flow from the tank T to the ram cylinder through the connection 39, the port 36, the lining apertures 32, channel 30 and passage 27. In the left hand position of the piston valve the apertures 32 are uncovered to permit the passage of the fluid rearwardly of the piston head. There is thus a free passage for the admission of relatively low pressure tank fluid to the ram cylinder for the first part of the working stroke of the ram. Were it not for the exhaust restriction 58 the tank pressure constantly present at the left of the piston valve might, in some apparatus, predominate too quickly and force the piston valve to the right to close the apertures 32 and shut off the admission of tank fluid to the ram cylinder too early in the ram stroke. By the use of a restriction plug this movement may, when necessary, be properly timed. In the present adjustment of the control valve 45 the port 49 in the valve seat is uncovered and the fluid at pump pressure which is constantly in the valve chest is free to flow therefrom through the connection 50 to the port 37 of the casing 1 and into the small cylinder 3. Here, however, it is trapped by the packing of the piston valve stem and prevented from flowing to the ram cylinder until the latter portion of the ram stroke.

When the pressure to the right of the piston valve 8 has reduced sufficiently through the restriction 58 the valve is moved to the right to bring the packing sleeve 20 beneath

the port 37 and permit the high pressure pump fluid to flow around said sleeve, through the apertures 20^a, the lining apertures 33, the channel 31, and out through the 5 passage 27 to the ram cylinder. This access of high pressure pump fluid gives the ram its working pressure. The admission of this high pressure is properly timed by the restriction plug 58 whose capacity is chosen 10 in accordance with the size of the press and the results required. The plug may be readily replaced by other plugs of different capacities to adapt the valve device to work properly with different presses. The use of 15 the restriction plug 58 to control the exhaust is desirable in order to permit the use of a large port 35 to provide for a quick in-flow of fluid for the operation of the valve 8, and at the same time provide a properly timed exhaust through said port 35.

When the ram is to be retracted to release the pressure, the operator operates the lever 47 to move the pilot valve to release position shown in Fig. 7. The valve then closes the 25 port 49 and shuts off the flow of high pressure pump fluid to the ram cylinder through the connection 50. It also closes the ports 51^a and 52^a and uncovers the ports 51 and 52. The exhaust from the casing 1 to the right of 30 the piston valve 8 is then shut off and high pressure pump fluid flows from the valve chest 44 to the casing through the port 52, connection 56 and port 35 of the cylinder head. This accession of high pressure fluid predominates over the tank fluid pressure at 35 the left of the piston valve and forces the valve back to the left, uncovering the apertures 32. Simultaneously high pressure pump fluid is admitted to the ram draw-back 40 cylinders through the valve chest 44, the port 51 and the connection 55. This fluid raises the draw-back pistons and elevates the ram. Since the apertures 32 have been uncovered 45 the fluid displaced by the rising ram is forced through them and back through the connection 39 to the supply tank T. Thus it will be seen that the ram is entirely controlled by two simple movements of the pilot valve. The valve is moved in either direction until 50 it abuts fixed stops so that no skill or care is required for its operation. Having so operated the pilot valve the fluid pressure operated valve can be relied upon to automatically control the ram movements in the proper manner.

While I have illustrated and described what I now consider the preferred embodiment of my invention I do not wish to be limited to this precise disclosure but reserve the right to make such changes as will lie within the scope of the claims. The location and character of the restriction means 58, for example, is capable of being varied without departing from the spirit of the invention. 60 In the claims the terms "supply tank" and

"pump" include as equivalents any suitable sources of relatively low pressure fluid and high pressure fluid respectively.

What I claim is:

1. A valve device for controlling the movements of a hydraulic press ram, comprising a valve casing; a fluid pressure operated valve mounted to reciprocate in said casing; a connection through said casing and under the control of the valve to permit exchanges 70 of fluid between a supply tank and the ram cylinder; a connection under the control of said valve to lead fluid under pump pressure through the casing to the ram cylinder; a connection to lead tank fluid to the casing for 75 moving the valve in one direction to establish said pump pressure and ram cylinder connection and to close said tank and ram cylinder connection; and a connection to lead fluid under pump pressure to the casing for 80 moving the valve in the reverse direction to close the pump pressure and ram cylinder connection and to re-establish the connection between the ram cylinder and tank.

2. An apparatus for controlling the movements of a hydraulic press ram, comprising a valve casing; a fluid pressure operated valve mounted to reciprocate in said casing; a connection through said casing and under the control of the valve to permit exchanges 90 of fluid between a supply tank and the ram cylinder; a connection under the control of said valve to lead fluid under pump pressure through the casing to the ram cylinder; a connection to lead tank fluid to the casing for 95 moving the valve in one direction to establish said pump pressure and ram cylinder connection and to close said tank and ram cylinder connection; a connection to lead fluid under pump pressure to the casing for 100 moving the valve in the reverse direction to close the pump pressure and ram cylinder connection and to re-establish the connection between the ram cylinder and tank; and manually operable means to control the admission and exhaust of said valve-moving pump fluid and thereby cause the valve movements.

3. An apparatus for controlling the movements of a hydraulic press ram and ram draw-back means, comprising a valve casing; a fluid pressure operated valve mounted to reciprocate in said casing; a connection through said casing and under the control of the valve to permit exchanges of fluid 115 between a supply tank and a ram cylinder; a connection under the control of said valve to lead fluid under pump pressure through the casing to the ram cylinder; a connection to lead tank fluid to the casing for moving the valve in one direction to establish said pump 120 pressure and ram cylinder connection and to close said tank and ram cylinder connection; a connection to lead fluid under pump pressure to the casing for moving the valve in reverse direction to close the pump pressure 125

130

and ram cylinder connection and to re-establish the connection between the ram cylinder and tank; and control means to simultaneously admit pump fluid to the valve 5 casing and to the ram draw-back means in one position and to simultaneously exhaust pump pressure from the valve casing and from the draw-back means in another position, thereby to cause the valve and ram move- 10 ments.

4. An apparatus for controlling the movements of a hydraulic press ram and ram draw-back means, comprising a valve casing; a fluid pressure operated valve mounted to reciprocate in said casing; a connection through said casing and under the control of the valve to permit exchanges of fluid between a supply tank and the ram cylinder; a connection under the control of said valve 15 to lead fluid under pump pressure through the casing to the ram cylinder; a connection to lead tank fluid to the casing for moving the valve in one direction to establish said pump pressure and ram cylinder connection 20 and to close said tank and ram cylinder connection; a connection to lead fluid under pump pressure to the casing for moving the valve in reverse direction to close the pump pressure and ram cylinder connection and to 25 re-establish the connection between the ram cylinder and tank; and manually operable control means to simultaneously admit pump fluid to the valve casing and to the ram draw-back means and to simultaneously exhaust 30 pump pressure from the valve casing and from the draw-back means, thereby to cause the valve and ram movements.

5. A valve device for controlling the movements of a hydraulic press ram, comprising a valve casing; a fluid pressure operated valve mounted to reciprocate in said casing; a connection through said casing and under the control of said valve to permit exchanges of fluid between a supply tank and the ram cylinder; a connection to lead tank fluid to the casing for moving the valve in one direction to close said ram cylinder and tank connection; and a connection to lead fluid under 45 pump pressure to the casing for moving the valve in the reverse direction to re-establish the tank and ram cylinder connection.

6. An apparatus for controlling the movements of a hydraulic press ram, comprising a valve casing; a fluid pressure operated valve mounted to reciprocate in said casing; a connection through said casing and under the control of said valve to permit exchanges of fluid between a supply tank and the ram cylinder; a connection to lead tank fluid to the casing for moving the valve in one direction to close said ram cylinder and tank connection; a connection to lead fluid under pump pressure to the casing for moving the valve in the reverse direction to re-establish 55 the tank and ram cylinder connection; and

means to control the admission and exhaust of said valve-moving pump pressure and thereby cause the valve movements.

7. A valve device for controlling the movements of a hydraulic press ram, comprising 70 a valve casing; a fluid pressure operated valve mounted to reciprocate in said casing; a connection under the control of said valve to lead fluid under pump pressure through the casing to the ram cylinder; a connection 75 to lead fluid from a tank to the casing for moving the valve in one direction to open said pump and ram cylinder connection; and a connection to lead fluid under pump pressure to the casing for moving the valve in 80 the reverse direction and closing the pump and ram cylinder connection.

8. An apparatus for controlling the movements of a hydraulic press ram, comprising 85 a valve casing; a fluid pressure operated valve mounted to reciprocate in said casing; a connection through said casing and under the control of the valve to permit exchanges of fluid between a supply tank and the ram cylinder; a connection under the control of said valve to lead fluid under pump pressure through the casing to the ram cylinder; a connection to lead tank fluid to the casing for moving the valve in one direction to establish 90 said pump pressure and ram cylinder connection and to close said tank and ram cylinder connection; a connection to lead fluid under pump pressure to the casing for moving the valve in the reverse direction to close the pump pressure and ram cylinder connection 95 and to re-establish the connection between the ram cylinder and tank; control means to admit said valve-moving pump fluid to the casing; and means to exhaust said valve-moving fluid at a slower rate than its rate of admission thereby to retard the movements of the valve by the tank fluid.

9. An apparatus for controlling the movements of a hydraulic press ram and ram draw-back means, comprising a valve casing; a fluid pressure operated valve mounted to reciprocate in said casing; a connection through said casing and under the control of the valve to permit exchanges of fluid between a supply tank and the ram cylinder; a connection under the control of said valve to lead fluid under pump pressure through the casing to the ram cylinder; a connection to lead tank fluid to the casing for moving the valve in one direction to establish said pump pressure and ram cylinder connection and to close said tank and ram cylinder connection; a connection to lead fluid under pump pressure to the casing for moving the valve in reverse direction to close the pump pressure and ram cylinder connection and to re-establish the connection between the ram cylinder and tank; control means to simultaneously admit pump fluid to the valve casing and to the ram draw-back means in one position and 100

to simultaneously exhaust pump pressure from the valve casing and from the draw-back means in another position, thereby to cause the valve and ram movements; and 5 means to restrict the exhaust of said valve-moving pump fluid from the casing thereby to retard the movement of the valve by the tank fluid.

10. An apparatus for controlling the movements of a hydraulic press ram, comprising a valve casing; a fluid pressure operated valve mounted to reciprocate in said casing; a connection through said casing and under the control of the valve to permit exchanges of fluid between a supply tank and the ram cylinder; a connection under the control of said valve to lead fluid under pump pressure through the casing to the ram cylinder; a connection to lead tank fluid to the casing for 15 moving the valve in one direction to establish said pump pressure and ram cylinder connection and to close said tank and ram cylinder connection; a connection to lead fluid under pump pressure to the casing for moving the valve in the reverse direction to close the pump pressure and ram cylinder connection and to re-establish the connection between the ram cylinder and tank; means to 20 control the admission and exhaust of said valve-moving pump fluid and thereby cause the valve movements; and means to retard the movement of the valve by the tank fluid.

11. A hydraulic press apparatus comprising a ram cylinder; a ram therein; a fluid pressure operated draw-back mechanism connected to the ram; a fluid pressure operated ram control valve device connected to the ram cylinder to direct fluid to and from the latter; and a manually operable pilot valve to control the movements of the fluid pressure operated valve device and the draw-back mechanism.

12. A hydraulic press apparatus comprising a ram cylinder; a ram therein; a fluid pressure operated draw-back mechanism connected to the ram; a pump; a supply tank; a fluid pressure operated reciprocable valve device connected to the ram cylinder and to the supply tank to permit a fluid flow between the tank and the ram cylinder; means whereby fluid pressure from the tank will tend to move the reciprocable valve in one direction to close communication between the tank and the cylinder; means connecting the pump to the fluid pressure valve to permit pump fluid to move the reciprocable valve in the opposite direction to open communication between the pump and the ram cylinder; and a valve controlling communication between the pump, the draw-back mechanism and the valve device and between the said valve device and an exhaust port.

13. A hydraulic press apparatus comprising a ram cylinder; a ram therein; a fluid

pressure operated draw-back mechanism connected to the ram; a pump; a supply tank; a fluid pressure operated reciprocable piston valve device connected to the ram cylinder and to the supply tank to permit a fluid flow between the tank and the ram cylinder, said piston valve having an enlarged head at one end; means whereby the enlarged head of said piston valve will be subject to fluid pressure from the tank to move the reciprocable valve to close communication between the tank and the cylinder; means connecting the pump to the fluid pressure valve to subject the smaller end of the piston valve to fluid pressure from the pump to move the reciprocable valve to open communication between the ram cylinder and the tank; and a valve in one position controlling communication between the pump, the draw-back mechanism and the valve device and in another position controlling communication between the said valve device and an exhaust port.

14. A hydraulic press apparatus comprising a ram cylinder; a ram therein; a supply tank; a fluid pressure operated draw-back mechanism connected to the ram; a fluid pressure operated ram control valve device connected to the ram cylinder to direct fluid to and from the latter; a single manually operable pilot valve having an application position and a release position, the said pilot valve in application position controlling the delivery of pump pressure to the ram cylinder through the control valve device, and also controlling the exhaust of said pump pressure from the control valve device thereby to permit the tank pressure to move said device into position to permit the pump pressure to flow to the ram cylinder; means whereby the manually operable pilot valve in application position will exhaust pressure from the draw-back mechanism; and means whereby said pilot valve in its release position will connect the pump to the draw-back mechanism and to the reciprocable control valve device to move said valve device into position to connect the ram cylinder to the tank.

15. A hydraulic press apparatus comprising a ram cylinder; a ram therein; a tank; a press pump; a fluid pressure operated reciprocable ram control valve, means connecting the control valve to the tank to direct tank pressure against one end of the valve; a connection between the pump and the said valve; means whereby the control valve in one position will connect the pump to the ram cylinder and close communication between the tank and the ram cylinder; means whereby the control valve in another position will open communication between the ram cylinder and the tank and close communication between the ram cylinder and the pump; means to deliver pump pressure against one end of the reciprocable control valve to op-

pose tank pressure delivered against the other end of the said valve, said pump pressure moving the said valve into position to connect the pump to the ram cylinder; a manually operable pilot valve, in application position controlling the delivery of the pump pressure to the control valve for moving the ram on its working stroke, and the exhaust of said valve-moving pump pressure from the control valve thereby to permit the tank pressure to move the control valve to permit pump pressure to flow to the ram cylinder; hydraulic draw-back means connected to the ram; and means whereby the manually operable pilot valve in application position will exhaust pressure from the draw-back mechanism, and in its release position will connect the pump to the draw-back mechanism, and to the reciprocable control valve to move said valve to position to connect the ram cylinder to the tank.

16. An apparatus for controlling the movements of a hydraulic press ram comprising a valve casing; a fluid pressure operated valve mounted to shift in said casing; a connection through said casing and under the control of the valve to permit exchanges of fluid between a supply tank and the ram cylinder; a connection under the control of said valve to lead fluid under pump pressure through the casing to the ram cylinder; a connection to lead tank fluid to the casing for moving the valve in one direction to establish said pump pressure and ram cylinder connection and to close said tank and ram cylinder connection; a connection to lead fluid under pump pressure to the casing for moving the valve in the reverse direction to close the pump pressure and ram cylinder connection and to re-establish the connection between the ram cylinder and tank; and manually operable means to control the admission and exhaust of said

valve moving pump fluid and thereby cause the valve movements.

17. A valve device for controlling the movements of a hydraulic press ram, comprising a valve casing defining a large cylinder and a small cylinder disposed end to end and communicating with each other; a fluid pressure operated valve forming a large piston and a small piston mounted to reciprocate in said large and small cylinders respectively, the small piston extending from one end of the larger one and reducing the face thereof; a connection leading transversely through said large cylinder to permit exchanges of fluid between a supply tank and the ram cylinder, adapted to be opened by the outward movement of the large piston and closed by inward movement thereof; a connection leading transversely through said small cylinder to conduct fluid under pressure through the casing to the ram cylinder, adapted to be opened by outward movement of the small piston and closed by inward movement thereof; a connection to lead tank fluid to the outer end of the large cylinder for moving the valve in one direction to establish said pump pressure and ram cylinder connection and to close said tank and ram cylinder connection; a connection to lead fluid under pump pressure to the outer end of the small cylinder for moving the valve in the reverse direction to close the pump pressure and ram cylinder connection and to re-establish the connection between the ram cylinder and tank; and manually operable means to control the admission and exhaust of said valve-moving pump fluid and thereby cause the valve movements.

In testimony whereof I hereunto affix my signature.

GEORGE DALE.
